UNITED STATES PATENT OFFICE.

FRANK RAWSON, OF RAWLINS, WYOMING.

FIRE-POKING APPARATUS.

Application filed January 24, 1927. Serial No. 163,252.

This invention relates to means for removing ashes, clinkers and other accumulation from the bed of a fire in locomotive and other steam boiler furnaces to maintain a clear and bright fire which is essential to a full head of steam when running at a high speed.

The invention contemplates a rake-like appliance arranged below and adjacent the 10 grate, with its teeth opposite the spaces formed between the grate bars, and means for operating the appliance to project the teeth thereof into the bed of the fire for agitating the same, thereby dislodging ashes, 15 clinkers and other accumulation.

While the drawings illustrate a preferred embodiment of the invention, it is to be understood that in adapting the means to meet specific needs and requirements, the design 20 may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a fragmentary sectional view 30 of a locomotive engine illustrating the application of an embodiment of the invention.

Figure 2 is an enlarged detail sectional view on the line 2—2 of Figure 1.

Figure 3 is a fragmentary perspective 35 view of the appliance.

Corresponding and like parts are referred to in the following description and designated in the several views of the drawings by like reference characters.

The numeral 1 designates the fire grate of the boiler furnace, the same being of usual or any preferred construction. A poking 40 appliance is provided for each section of the grate and consists of a bar 2 and teeth 3 projecting upwardly from the bar 2 and disposed opposite the spaces formed between the bar or like element of the grate. The terminal teeth 4 are of a greater length than the intermediate teeth, so as to normally extend 45 into the spaces formed between the end grate bars, as shown most clearly in Figure 50 2. The intermediate teeth 3 normally occupy

a position at the bottom of the grate to prevent injury thereto from the fire. The end teeth 4 function as guides to direct the 55 appliance so as to insure the several teeth passing between the grate bars, so as to agitate the fuel bed and dislodge ashes, clinkers and the like.

It is observed that the poking appliance 60 resembles a lawn rake and the several appliances are connected for simultaneous operation. An eye 5 is provided centrally of the bar 2 and receives a rod 6, a clamp screw 7 serving to secure each of the appliances to 65 the rod 6. A stem 8 depends from the rod 6 and one end of a lever 9 is coupled thereto, the other end of the lever being connected to a lever 10 by means of a link 11 while the lever 10 is conveniently disposed within 70 the cab of the engine, or other place for ready operation when it is required to poke the fire. It is observed that the arrangement is such as to admit of the apparatus being operated as a unit by means of a single part, 75 as the lever 10, which is arranged in the most advantageous and convenient position for manipulation when required.

Guides 12 are provided to cooperate with the teeth 4 to direct the device in its vertical movements. These guides 12 are, for convenience, attached to the ends of the grate sections and are open at their inner sides to receive the bar 2 when moved upwardly.

Having thus described the invention, I 85 claim:

1. The combination with a fire grate and guides pendant therefrom, of a fire poking device consisting of a toothed bar disposed beneath the grate and having certain teeth 90 of greater length than the remaining teeth and engaging the pendant guides to direct the device in its vertical movement.

2. The combination with a fire grate and guides pendant from opposite sides thereof, 95 of a fire poking device disposed beneath the grate and consisting of a bar having teeth projecting upwardly therefrom, the end teeth being of greater length than the remaining teeth and engaging the said guides 100 to direct the device in its vertical movement.

In testimony whereof I affix my signature.

FRANK RAWSON. [L.S.]
